IRONER

George W. Wardwell, Jr., Nichols, Conn., assignor
to General Electric Company, a corporation of
New York

Application September 18, 1937, Serial No. 164,529

9 Claims. (Cl. 38—61)

The present invention relates to rotary ironers of the type having cooperating ironing members comprising a roll and a shoe.

The object of my invention is to provide an improved construction and arrangement in rotary ironers, and for a consideration of what I believe to be novel and my invention, attention is directed to the accompanying description and the claims appended thereto.

10 In the accompanying drawings, Fig. 1 is a perspective view of a rotary ironer embodying my invention; Fig. 2 is an end view of the ironer showing the shoe pressed against the roll; Fig. 3 is an end view of the ironer showing the shoe moved away from the roll; Fig. 4 is a sectional front elevation of the ironer; Fig. 5 is an enlarged sectional view of the mechanism for moving the shoe toward and away from the roll; and Fig. 6 is a fragmentary view showing the construction for supporting the ironer on the wringer post of a domestic washing machine.

Referring to the drawings, the ironer comprises a frame 1 on which is supported a roll 2, a shoe 3, and the mechanism for driving the roll and for moving the shoe toward and away from the roll. As shown in Fig. 6, the frame has a depending tubular portion 4 having a flange 5 at its lower end which rests on a collar 6 secured to the upper end of the wringer post 7 of a domestic washing machine. Suitable means (not shown) are provided for preventing rotation of the ironing frame on the wringer post. Extending upward through the wringer post is a shaft 8 which is continuously driven by the washing machine mechanism. The shaft is journaled in a bearing 9 fixed to the upper end of the wringer post. Fixed on the end of the shaft is a pinion 10 which meshes with a crown gear 11 keyed to a shaft 12 journaled in bearings 13 in a boss 14 in the side wall 14^a of the frame. The frame has outwardly extending walls 15 providing a compartment or housing for the gears 10 and 11. The end wall of this compartment is provided by a removable closure plate 16.

50 The roll is of the construction shown in my application Serial No. 64,480, filed Feb. 18, 1936. It comprises a sheet metal cylinder 17 on the outer surface of which is a pad 18 held in place by a pad cover 19. The pad cover is held in place by snap rings 20 which fit in grooves 21 in the inner surface of the cylinder. Within the ends of the cylinder are disks 22 and 23 having outwardly extending flanges 24 and 24^a respectively fixed to the inner surface of the cylinder.

At the center of the disks 22 and 23 are sleeves 25 and 26 having outwardly extending flanges 27 and 28 respectively secured to the disks 22 and 23 and having sleeve bearings 29 and 30 respectively fixed therein. The sleeve bearings 29 and 30 bear respectively on collars 31 and 32 which loosely surround a tube 33 fixed in a boss 34 in the side wall of the ironer frame. The collars 31 and 32 are non-rotatably supported on the tube 33 in the manner shown at the right of Fig. 4. Within the tube 33 are cup-shaped seats 35 and 36 having tubular shanks 37 and 38 extending into diametrically opposite openings in the walls of the tube 33 arranged on a center line connecting the roll and shoe when the shoe is pressed against the roll. The shank 37 is slidable in its opening and the shank 38 is fixed in its opening. Extending through the tubular shanks 37 and 38 are pins 39 the upper ends of which fit in seats 40 in the inner surface of the collars 31 and 32 and the lower ends of which extend through openings 41 in the collars and are flush with the outer surfaces thereof. Between the seats 35 and 36 and around the pins 39 are helical compression springs 42. The springs 42 are strong enough to normally bias the collars 31 and 32 upward so that the lower parts, i. e., the parts corresponding to the part of collar 32 shown spaced from the tube in Fig. 4, are normally held against the under side of the tube 33. The pressure from the springs 42 is transmitted to the collars 31 and 32 through the shanks 37 of the seats 35. The supporting arrangement for the collar 31 is identical with the support for the collar 32.

When the shoe is away from the roll, the collars 31 and 32 will be urged against the under side of the tube 33 and the roll will occupy the position as shown in Fig. 3. In this position an internal gear 43 which is fixed to the flange 24^a, for example, by screws 44 threaded into the gear from the outside of the cylinder 17, will be out of mesh with a pinion 45 fixed to the continuously driven shaft 12. When the shoe is 45 pressed against the roll the pressure of the shoe on the roll overcomes the relatively weak springs 42 and moves the roll transversely with respect to the tube 33 to the position shown in Figs. 2 and 4. In this position the internal gear 43 meshes with the pinion 45 completing a driving connection to the roll. Since the springs 42 are relatively weak, rotation of the roll is started before full ironing pressure is developed between 50 55

the roll and the shoe. This decreases the starting load on the roll.

As the internal gear is moved into mesh with the pinion 45 there is a possibility of clashing of the gear teeth. This tendency for clashing is increased by the fact that the pinion 45 is an external gear with the teeth extending radially outward and the gear 43 is an internal gear with the teeth extending radially inward. It is, therefore, possible for a pair of teeth on the pinion to straddle a pair of teeth on the internal gear. Under this condition further approach of the gear teeth would cause serious jamming. This tendency for clashing or jamming of the gear teeth is prevented by the yieldable mounting for the roll provided by the collars 31 and 32. As the internal gear is moved into mesh with the pinion 45, if the teeth are in a position to cause jamming, the right end of the roll, as shown in Fig. 4, will pause in its movement while the left end of the roll will continue its movement. During the pause in the movement of the right end of the roll the teeth of the continuously rotating pinion 45 will move to a position in which the teeth may mesh without jamming.

Under some circumstances it is desirable that the roll remain stationary when the shoe is pressed against the roll. This is accomplished by moving a block 46 between the collar 32 and the upper side of the tube 33 when the shoe is away from the roll. Under this condition, the upper side of the collar 32 will be spaced from the upper side of the tube 33 to permit insertion of the block 46. The block 46 prevents movement of the collar 32 transverse to the tube 33 and thereby holds the internal gear 43 out of mesh with the pinion 45 when the shoe is pressed against the roll. The block 46 is carried on a slide 47 which projects between the tube 33 and the collar 31 to the outer end of the roll. A handle 48 is provided on the outer end of the slide. The slide is provided with a slot 49 through which the pin 39 of the collar 31 projects and a slot 50 through which extends a screw 50^a. The head of the screw 50^a overlaps the ends of the slot 50 preventing displacement of the slide.

The inner end of the roll is closed by a guard plate 51 fitting over the boss 34 which covers the teeth of the gears 43 and 45. Lengthwise movement of the roll is prevented by a thrust washer 52 mounted between the inner end of the boss 34 and the flange 28 and by a thrust washer 53 pinned to the outer end of the tube 33 and bearing against the flange 27.

The construction of the shoe is shown in Fig. 4. It comprises an arcuate metal plate 54 having studs 55 welded to its rear surface around which are arranged sleeves 56. A cover plate 57 is clamped between the sleeves 56 and cap nuts 60 threaded on the studs. Between the cover plate and the rear surface of the plate 54 are arranged suitable electric heating units (not shown). At the center of the shoe is a U-shaped bracket 58 fixed to a strip 59 and clamped between the cover plate and two of the sleeves 56. Between the arms of the bracket 58 extends a U-shaped bracket 60 the arms of which are welded to a sleeve 61 keyed to a shaft 62. The brackets 58 and 60 are pivotally connected by a pin 63 passing through the arms of the brackets and held in place by snap rings 64. There is sufficient clearance between the pin 63 and the bracket arms so that the shoe may have a tilting movement sufficient to equalize the pressure between the shoe and the roll. The sleeve 61 is held on the

shaft 62 between a shoulder 65 and a snap ring 66. The brackets 58 and 60, as shown in Figs. 2 and 3, comprise the links of a toggle for moving the shoe toward and away from the roll. When the shoe is pressed against the roll the rock shaft 62 and the common pivot point of the toggle links, the pin 63, lie slightly below a center line passing through the shoe and the roll. When the shoe is away from the roll, as shown in Fig. 3, the pivotal movement of the bracket 58 is limited by ears 67 struck out of the side walls of the bracket 60.

As the shoe is moved into engagement with the roll, the rotation of the roll starts, as explained above, before the development of full ironing pressure. The friction exerted on the shoe by the roll tends to straighten the toggle decreasing the force required to press the shoe against the roll.

The shoe operating shaft 62 is journaled at one end in an arm 68 projecting from the ironer frame 1. The free end of the shaft 62 extends along the roll and has sufficient resilience to equalize the pressure between the roll and the shoe due to variations in the thickness of the pad on the roll and of the material being ironed. Lengthwise movement of the shaft 62 in its bearing is prevented by a pin 69 bearing on a thrust washer 70 and by an arm 71 pinned to the shaft. The arm 71 serves as a crank arm for oscillating the shaft 62. In the outer end of the arm 71 is a bolt 72 (Fig. 5) on which is pivoted a connecting rod 73. The connecting rod is arranged between washers 74 and 75 on the bolt 72 and the sides and opening in the connecting rod around the bolt 72 are tapered as at 76 and 77 to permit pivotal movement of the connecting rod 73 about axes perpendicular to the bolt 72. The other end of the connecting rod 73 has a pin 78 fixed therein which is slidable in an opening 79 in a crank 80 loosely mounted on a reduced portion 81 of the shaft 12. The crank is held on the shaft by a screw 82 threaded into the end of the shaft. The inner surface of the crank 80 bears against a disk 83 fixed to the shaft 12, for example by threading the hub 84 of the disk on a threaded portion 85 of the shaft. The hub 84 of the disk projects through an opening 86 in the cover plate 16. As shown in Fig. 4 the hub 84 engages the outer surface of the crown gear 11 and holds it in place on the shaft. In the disk 83 are series of openings 87 of the same size as the opening 79 in the crank 80. A leaf spring 88 arranged between the connecting rod 73 and the crank 80 biases the connecting rod to a position in which the pin 78 is clear of the openings 87. In this position the connecting rod is held against the inner surface of a plate 89 having an angular portion 90 fixed to the outer end of the frame arm 68. The plate 89 is provided with a stiffening rib 91. In this position, the pin 78 fits in one of two slots or notches 92 and 92^a in the plate 89 as shown in Fig. 5. The notches 92 and 92^a are located in positions corresponding to the positions of the connecting rod shown in Figs. 2 and 3. In either of these positions the connecting rod 73 is disconnected from the shaft 12 and accordingly remains at rest.

To establish a driving connection between the shaft 12 and the connecting rod 73, the connecting rod is moved toward the disk 83 until the pin 78 enters one of the openings 87 in the disk, thus connecting the crank 80 to the disk. In this position the other end of the pin 78 is clear of the slots 92 and 92^a. The arrangement shown for

moving the connecting rod 73 into engagement with the disk 83 comprises a lever 93 pivoted between arms 94 fixed to the outside of the plate 89. Screws 95 are threaded through the arm opposite the slots 92 and 92^a, the inner ends of which provide stops or abutments for engaging the pin 78 and moving it into one of the holes 87 in the disk 83. A coil spring 96 arranged around stud 97 biases the lever 93 to the position shown in Fig. 5 in which the screws 95 are out of contact with the pin 78, the outward movement being limited by a pin 98 in the stud. Upon movement of the lever 93 toward the disk 83 one of the screws 95 will engage the end of the pin 78 and move it out of the slot 92 or 92^a and into one of the openings 87 in the disk 83 connecting the crank 80 to the disk 83. Since there are a larger number of openings 87 there is no perceptible delay in making this connection. The slots 92 and 92^a are provided with inclined cam surfaces 99 which cooperate with the end of the pin 78 and force it into the openings 87 in case the pin is not initially moved far enough. As soon as the crank 80 has rotated to a position in which the pin 78 is no longer opposite one of the slots 92 or 92^a the pin will be held in the driving position by the face of the plate 89 which prevents outward movement of the pin. The lever 93 may, therefore, be released. As soon as the crank has rotated through 180°, the pin 78 will be opposite one of the slots 92 or 92^a and will be moved therein by the spring 88 breaking the connection between the crank 80 and the disk 83. The arrangement shown provides a convenient arrangement for rotating the crank 80 in steps of 180°.

The slots 92 and 92^a are placed so that the connecting rod is moved between the positions shown in Figs. 2 and 3. In the position shown in Fig. 2, the shoe is pressed against the roll. Since the roll is rotating in a clockwise direction in order to feed the material being ironed beneath the shoe, the friction exerted on the shoe by the roll tends to turn the shaft 62 in a counterclockwise direction. This force would tend to move the connecting rod 73 in the direction of the arrow 100. Such movement is prevented by the fact that the crank 80 lies along the axis of the connecting rod 73 and is connected to the connecting rod by the pin 78.

It is to be noted that since the toggle links 58 and 60 are substantially in alignment, and since the force of friction on the shoe tends to straighten the toggle, very little force is required from the connecting rod 73 to press the shoe against the roll. From another aspect, this means that the disengagement of the pin 78 from the disk 83 will be correspondingly small. When the parts are in the position shown in Fig. 3 the force of gravity acting on the shoe to turn the shaft 62 in a counterclockwise direction and therefore tends to move the connecting rod in the direction of the arrow 101. Such movement is prevented by the fact that the crank 80 lies along the axis of the connecting rod 73. The crank is, therefore, in effect on dead center. Furthermore, movement of the connecting rod in the direction of the arrow 101 would be prevented by engagement of the pin 78 with the edges of the slot 92^a.

In the use of the ironer the material to be ironed is arranged on the surface of the roll while the shoe is separated from the roll. In this position the internal gear 43 is separated from the pinion 45 and the roll is accordingly stationary. The lever 93 is then actuated to move the pin 78

out of the slot 92^a and into one of the openings 87 in the disk 83 connecting the disk 83 to the crank 80. As soon as the crank has rotated to a position in which the pin is no longer opposite the slot 92 the lever 93 may be released and the pin will be held in the driving position by the inner surface of the plate 89. When the crank 80 has moved through 180° and the pin has moved through 180° the pin is moved into the slot 92 breaking the connection between the disk 83 and the crank 80. The parts now occupy the position shown in Fig. 2 in which the shoe is pressed against the roll. In this condition the roll occupies the position shown in Fig. 4 in which the internal gear is in mesh with the pin 45 and the roll is accordingly rotated. Upon completion of the ironing, actuation of the lever 93 in the manner described above will cause rotation of the crank 80 to the position shown in Fig. 3 in which the shoe is separated from the roll.

What I claim as new and desire to obtain by Letters Patent of the United States is:

1. In an ironer, cooperating ironing members comprising a roll and a shoe, a shaft, means supporting the shaft for rotation on its axis, a toggle forming the sole means for supporting one of the ironing members on the shaft and for moving it into and out of engagement with the other ironing member, said toggle comprising a link fixed to said shaft and a second link pivoted to the first link and connected in supporting relation to the supported ironing member, the common pivot point of said links and the shaft lying substantially on a center line connecting the ironing members when the ironing members are in engagement, and power means having connections for selectively rotating the shaft on its axis and for rotating the roll.

2. In an ironer, a roll, a shoe, a frame having provisions for supporting the roll, a rock shaft supported in the frame for rotation on its axis, a toggle forming the sole means for supporting the shoe on the shaft and for moving it into and out of engagement with the roll, said toggle comprising a link fixed to the shaft and a second link pivoted to the first link and fixed to the shoe, the common pivot point of said links and the rock shaft lying substantially on a center line connecting the roll and the shoe when the roll and shoe are in engagement, and power means having connections for selectively rotating the shaft on its axis and for rotating the roll.

3. In an ironer, a roll, a shoe, a frame having provisions for supporting the roll, a rock shaft supported in the frame for rotation on its axis, a toggle forming the sole means supporting the shoe on the shaft and for moving it into and out of engagement with the roll, said toggle comprising a link fixed to the shaft and a second link pivoted to the first link and fixed to the shoe, the common pivot point of said links and the rock shaft lying substantially on a center line connecting the roll and the shoe when the roll and shoe are in engagement, power means for oscillating the shaft on its axis whereby the shoe is moved toward and away from the roll and for rotating the roll, and means controlling the driving connection between said power means and the roll to start the roll prior to the development of full ironing pressure between the roll and the shoe, the direction of movement of the toggle being such that the force of the friction exerted on the shoe by the roll assists in straightening the toggle and pressing the shoe against the roll.

4. In an ironer, a roll, a shoe, a frame at one end of the roll having provisions for supporting the roll, a rock shaft journaled at one end in the frame for rotation on its axis and having its free end extending along the roll, said shaft having sufficient resilience to equalize the pressure between the roll and the shoe under varying ironing conditions, a toggle forming the sole means for supporting the shoe and for moving it into and out of engagement with the roll, said toggle comprising a link fixed to the shaft and a second link pivoted to the first link and fixed to the shoe, the common pivot point of said links and the rock shaft lying substantially on a center line connecting the roll and the shoe when the roll and shoe are in engagement, and power means having connections for selectively rotating the shaft on its axis and for rotating the roll.
5. In an ironer, cooperating ironing members comprising a roll and a shoe, power driving means including a driven shaft, a connecting rod beyond an end of said shaft connected to one of said ironing members for effecting engagement and separation of said ironing members upon reciprocation thereof, crank means having connections to said shaft and connecting rod for reciprocating the connecting rod, manually operable means for establishing the connection between the crank means and the connecting rod, means for automatically breaking said connection upon a predetermined reciprocation of the connecting rod, and a driving connection between the driving means and the roll for rotating the roll.
6. In an ironer, cooperating ironing members comprising a roll and a shoe, a rock shaft supported for rotation on its axis, a toggle forming the sole means for supporting the shoe on the rock shaft and for moving it into and out of engagement with the roll, said toggle comprising a link fixed to said shaft and a second link pivoted to the first link and connected in supporting relation to the shoe, the common pivot points of said links and the rock shaft lying substantially on a center line connecting the ironing members when the ironing members are in engagement, and power means for rotating the roll and for selectively oscillating the rock shaft on its axis, the direction of rotation of the rock shaft to press the shoe against the roll being such that the force of friction exerted on the shoe by the roll assists in pressing the shoe against the roll.
7. In an ironer, a roll, power means for rotating the roll, a rock shaft, a connecting rod, means connecting the connecting rod to the shaft for effecting oscillation of the shaft upon reciprocation of the connecting rod, a crank for reciprocating the connecting rod, a shoe, and means for supporting the shoe on the shaft whereby the shoe is moved toward and away from the roll by oscillation of the shaft, said supporting means being constructed and arranged so that the friction exerted on the shoe by the rotating roll tends to turn the shaft in a direction to cause the connecting rod to be under tension.
8. In an ironer, cooperating ironing members comprising a roll and a shoe, power driving means including a driven shaft, a connecting rod beyond an end of said shaft connected to one of said ironing members for effecting engagement and separation of said ironing members upon reciprocation thereof, a crank loose on the shaft, a clutch disk fixed to the shaft and having a series of openings therein, a pin fixed in the connecting rod and providing a pivotal connection to the crank, one end of said pin being slidable into one of said openings upon lateral movement of the connecting rod, means for biasing the connecting rod to a position in which the pin is clear of said openings and a plate engaging the other end of said pin for holding the pin in said openings, said plate having notches permitting movement of the pin out of said openings upon a predetermined rotation of the crank.
9. In an ironer, cooperating ironing members comprising a roll and a shoe, power driving means including a driven shaft, a disk fixed to the shaft connected to one of said ironing members having a series of openings therein, a crank loose on the shaft, a connecting rod for effecting engagement and separation of said ironing members upon reciprocation thereof, a pin extending through the crank and providing a pivotal connection between the crank and the connecting rod, means for moving one end of said pin into one of the openings in the disk for connecting the crank to the shaft, means for holding the pin in said opening during a predetermined rotation of the crank, and automatic means for disengaging the pin from said opening upon completion of said predetermined rotation of the crank.

GEORGE W. WARDWELL, JR. 50
